DIE FOR EXTRUSION PRESSES

Irving T. Bennett, Baltimore, Md., assignor to
Revere Copper and Brass Incorporated, Rome,
N. Y., a corporation of Maryland

Application October 16, 1948, Serial No. 54,846

1 Claim. (Cl. 207—17)

1 My invention relates to extrusion presses. The present invention has among its objects the provision of a die of improved construction for simultaneously extruding a plurality of hollow shapes from a single billet of metal, such as aluminum, separate streams of which are capable of being mixed under high pressure to form a homogeneous mass.

The invention will be best understood from the following description when read in the light of the accompanying drawings, the scope of the invention being more particularly pointed out in the appended claim.

In the drawings:

Fig. 1 is a longitudinal vertical section more or less diagrammatically showing a fragment of an extrusion press having an improved die according to the invention, this figure also illustrating a step in the extrusion process;

Fig. 2 is an elevation of the improved die as viewed from the left of said die in its position occupied in Fig. 1;

Fig. 3 is a section on the line 3—3 of Fig. 2, with parts omitted;

Fig. 4 is a bottom view of one of the mandrel carrying parts of the improved die as viewed in the position which said part occupies in Fig. 3;

Fig. 5 is a plan of one of the die parts having the die orifice according to Figs. 1, 2 and 3 as viewed in the position which said part occupies in Fig. 3;

Fig. 6 is a bottom view of the die part according to Fig. 5;

Fig. 7 is a transverse section of a tube representing an example of the shape to be extruded by the improved die;

Fig. 8 is a transverse section of a modified form of the tube according to Fig. 7;

Fig. 9 is a view corresponding to Fig. 2 of a prior art die;

Fig. 10 is a section on the line 10—10 of Fig. 9; and

Fig. 11 is a section on the line 11—11 of Fig. 10.

As will be understood by those skilled in the art, when extruding solid bars and like shapes the die of the extrusion press need have but a die orifice of cross-section corresponding to the exterior cross-sectional form of the shape. However, when the shape extruded by the press is hollow, the die must have a die orifice of cross-section corresponding to the cross-sectional form of the exterior surface of the shape, and, received by such die orifice, must have a mandrel of cross-section corresponding to the cross-sectional form of the interior surface of the shape. For example, in extruding the hollow shape exemplified by the tube 1 (Fig. 7) the die must have a die orifice defining the exterior surface 3 of the tube, and must have a mandrel

5 defining the interior surface 5 of the tube. Shapes of other cross-section as, for example, the tube 7 (Fig. 8) having the longitudinally extending opening 9, also require use of a mandrel, 10 which latter, or the die orifice, in the case of such a tube must be formed with a rib or the like for defining the form of such longitudinally extending opening. The use of a mandrel is imposed in this latter case because, were it attempted to form the die with a die orifice of cross-section defining the entire cross-sectional form of both the interior and exterior wall surfaces of the tube including those of the longitudinally extending opening 9, the thickness of the metal of the die defining such longitudinally extending opening would be too small under the high extrusion pressure required to afford sufficient strength for supporting the metal defining the rest of the interior form of the tube. Such tubular shapes, and shapes having a longitudinally extending opening requiring the use of a mandrel for extruding them, are in the art termed "hollow shapes," which term is employed herein in such sense.

In the embodiment of the invention illustrated there is provided a die body comprising a housing 11 carrying a plurality (herein four) of like pairs of cooperating die parts 13 and 15. As shown, the housing is shown with a plurality of openings 17, one for each pair of die parts 13 and 15, which openings are of circular cross-section and extend through said housing from its upper face 18 to its lower face 19 as viewed in Fig. 3. The portion 21 of each of these openings adjacent the face 18 is of enlarged diameter so as to form intermediate the length of the opening an annular shoulder 23 opposed to said face.

In the enlarged diameter portion 21 of each of the openings 17 of the housing 11 is removably received one of the die parts 13 and one of the die parts 15, these parts having exterior surfaces fitting the lateral cylindrical walls of that portion of the opening. The die part 13 at one end rests adjacent its periphery upon the annular shoulder 23 presented by the housing. This die part is formed with an axial opening 25 which adjacent the face of said part opposite the shoulder 23 is formed with an annular rib 27 provided with an orifice 29. This orifice 29 defines the exterior form of the shape to be extruded, said shape for convenience of illustration being shown as a square tube 1 according to Fig. 7.

Each die part 15 at one end rests against the adjacent face of the associated die part 13, the contacting faces of the two parts preferably being formed with the cooperating interfitting longitudinally projecting flanges 31 and 33 for facilitating holding them in axial alignment. The face of the die part 15 adjacent the die part 13

is formed with what from one aspect may be considered an annular recess 35 (Fig. 3) the inner walls of which are constituted by the outer longitudinally extending surfaces of a mandrel 37. The forward end of this mandrel is received within the die orifice 29 in spaced relation to the walls of that orifice, the mandrel being of such cross-sectional shape as to define the interior form of the tube or other shape to be extruded. Externally the mandrel carrying die part 15 is formed with a plurality, herein four, of longitudinally extending grooves 39 which at their inner ends communicate with the recess 35. From another aspect the die part 15 may be said to consist of the mandrel 37 carrying a plurality of radially projecting longitudinally extending ribs 41 (Figs. 2 and 4) in quartering relation of each other, which ribs at their outer extremities fit the lateral walls of the enlarged diameter portion 21 of the opening in the housing 11, the lower ends 20 of which ribs are provided with grooves collectively forming with the adjacent portions of the spaces between the ribs the recess 35.

As illustrated, for preventing relative rotation between the die parts 13 and 15 they are shown as keyed together by a pin 43 which may be fixed to the part 13 and be removably received in an opening 44 in the part 15, the die part 15 being preferably keyed by a pin 45 to the housing 11 for preventing it, and the die part 13 keyed to it, from rotation relative to the housing, the pin 45 being preferably fixed to the part 15 and removable with the latter from the housing.

As shown in Fig. 1, in accordance with common practice the die is removably mounted in the bore 47 of a die holder 49, which holder is removably mounted in a ring 50 removably carried by a support 51 movably mounted on the frame of the extrusion press, the support having an upwardly projecting portion 53 between which and the die and die holder are placed, removable blocks 55 and 57 for holding the face of the die opposite the blocks against the end of the extrusion press cylinder 59. This cylinder in the usual manner is provided with a bore 61 for the extrusion press ram 63 and dummy block 65, the latter during the extrusion operation bearing against a billet 67 such as aluminum. In operation pressure of the ram 63 on the billet 67 forces the metal of the billet through the grooves 39 of the die part 15 into the mixing chamber presented by the recess 35 of that part. In this chamber the streams of metal passing through the grooves are mixed, or, as it is sometimes termed "welded" under the high pressure existing to form a homogeneous mass of metal, which metal is forced through the space between the mandrel 37 and the walls of the die orifice 29 of the die part 13 to form the tubes 1, these tubes passing through the openings 17 of the housing 11 and through aligned openings 69, 71 and 73 in the blocks 55 and 57 and projection 53, respectively, until the metal of the billet is substantially exhausted. The support 51, with the blocks 55 and 57, ring 50, die holder 49 and the die, is then moved forward relative to the ram cylinder 59, carrying with them the unextruded butt end of the billet, which latter is then sheared off close to the adjacent face of the die. Then, after retraction of the ram, a fresh billet may be entered into the ram cylinder and the support 51 retracted to place the parts again in their positions shown by Fig. 1. Extruding this fresh billet forms continued lengths of the tubes or other shapes 1 welded at their

ends to the ends of those formed by the preceding extrusion operation. If desired, as is usually the case, the weld between the ends of the tubes may be cut out as the extrusion operation is performed so as to separate the lengths formed by successive extrusion operations. These operations of extruding the tubes from successive billets may be continued indefinitely without its being necessary to clear the die.

It will be observed that in the construction above described a die is provided for simultaneously extruding a plurality of like hollow shapes from a single billet, which die comprises a die body formed to present a plurality of separate non-communicating internal chambers in which the streams of metal entering said chambers from the billet are mixed to form separate homogeneous masses of metal, which masses are separately forced through the spaces between co-operating mandrels and die orifices defining the cross-sectional forms of the shapes.

Heretofore it has been proposed to extrude a plurality of shapes from a single billet by use of the die illustrated by Figs. 9, 10 and 11. This prior art die comprises the separable parts 75 and 77, the parts 75 being formed with a plurality of portholes 79 through which metal of the billet is forced by the ram into the annular chamber 81 formed in the part 77 and closed by the part 75. From this chamber lead all the die orifices 83 corresponding to the exterior form of the shape being extruded as, for example, square tubes 1 according to Fig. 7. The housing part 75 in this prior art die integrally carries the mandrels 85 which project forward into the openings 83 so as to define the interior form of the shape being extruded.

It will be observed that the prior art die above described distinguishes from the die according to the present invention in that, among other things, in the prior art die a single mixing chamber for the metal is provided for a plurality of die openings for extruding hollow shapes, instead of a separate mixing chamber for each of a plurality of die openings for extruding such shapes.

It has been found that by employing the separate mixing chambers in accordance with applicant's invention many unexpected and unobvious valuable results are secured. In the first place it has been found that with the separate mixing chambers lower extrusion pressures are required for extruding a plurality of hollow aluminum shapes of given cross-section than when employing a die having a single mixing chamber for extruding the same number of the same shapes, this despite the transverse cross-sectional area of the single mixing chamber of the prior art die being greater than the aggregate transverse cross-sectional area of the total number of mixing chambers of the die according to the present invention and even where at the same time the aggregate area of the total number of portholes 79 of the prior art die is greater than the aggregate cross-sectional area afforded by the total number of grooves 39 of the die according to the present invention. This lower extrusion pressure increases the life of the die, permits the use of less expensive die back-up blocks, and most importantly avoids distortion and deflection of the mandrels so that a more accurate and uniform product in respect to dimensions will be secured. It has also been found that a lower temperature of the aluminum billet is permissible with the improved die as compared to the prior art die, it

not being necessary to render the metal as plastic with the improved die as with the prior art die, which results when the improved die is employed in savings in heating costs and, as in the case of the reduced pressure necessary, also acts to secure a longer life of the die. Furthermore, the lower pressures and temperatures necessary when using the improved die for extruding aluminum permit the physical properties of the product to be more easily controlled during the extrusion operation, with the overall result of insuring a better product in respect to such properties. Still further, not only are lower temperatures and pressures required with the improved die, as compared to the prior art die, but a greater speed of extrusion of the aluminum can be secured despite such lower pressures and temperatures. In practice, when employing the prior art die, if the extrusion pressure required is near the maximum capable of being exerted by the press the latter will cease to operate if one die opening clogs, but when employing the die having separate mixing chambers for extruding the same number of the same shapes the press because of the lower pressures then required will not cease to operate if one die opening should clog for it can then take care of the increase in pressure necessary to extrude with the remaining unclogged die openings. Also extreme difficulty has been experienced in designing the prior art die with a single mixing chamber in respect to securing the necessary condition of causing the metal to extrude from all the die openings at substantially the same rate, the securing of such condition with the prior art die requiring the exercise of great skill and nicety of design on the part of the die maker. Such tendency of the metal to extrude from the die openings at different rates, it has been found, is substantially absent with a die according to the present invention employing a separate mixing chamber for each die opening, with the result that the improved die can be produced with greater facility and at lower cost. Still further, the cost of producing the improved die is reduced as compared to the prior die, and greater accuracy of manufacture is assured, because the improved die for the most part is formed of much smaller pieces of steel than the prior die. The making of the die in the way described gives it great versatility in respect to adapting it for extruding selected shapes, because the same may be secured by merely substituting small parts for each other, rather than substituting a complete die as would be the case with the prior die.

As an example of the above advantages secured by the improved die, it has been found, that where the available fluid pressure to be applied to the ram of the press limits the maximum size of the aluminum billet to one of $4\frac{1}{2}$ inches diameter when employing a multiple die having four openings and a single mixing chamber according to the prior art, an 8 inch diameter billet, in other words, one having about $3\frac{1}{4}$ times as much metal for a given length of ram cylinder bore, may be employed for the same number of die openings of the same shape and size when the improved die having separate mixing chambers is employed. This increase in the size of the billet according to this example will secure about $3\frac{1}{4}$ times the amount of hollow shapes produced during a single extrusion operation, and for a given amount of extruded shapes produced reduces to about one-third the overall loss in time required for shearing off the billet butts

and inserting fresh billets between extruding operations. As a further example of the advantages secured in practice by use of the improved die it has been found, that where a hot aluminum billet 6 inches in diameter and 21 inches long required from 3300 to 3600 pounds per square inch extrusion pressure for a die having four openings and a single mixing chamber according to the prior art die, the improved die according to the present invention having the same number of die openings for extruding exactly the same shapes required an extrusion pressure of but 2500 to 2700 pounds per square inch with a decrease in the necessary temperature of the billet from 925 to 850° F. and secured an increase in the linear speed of extrusion of the shapes from 40 to 90 feet per minute.

It will be understood that although the die illustrated is designed for simultaneously extruding four hollow shapes it may be designed for extruding a greater or lesser number. It will also be understood that, although as illustrated the die is designed for extruding square tubes, other forms of hollow shapes may be extruded with equal facility. Further, it will be understood that within the scope of the appended claim wide deviations may be made from the form of the invention illustrated and described without departing from the spirit of the invention.

30 I claim:

A die for simultaneously extruding a plurality of like hollow aluminum shapes from a single billet comprising a housing formed with a plurality of like openings, each of which openings 35 extends from one face of said housing to the other and is formed to present an annular shoulder intermediate its length, separate like first die parts each removably received by and fitting one of said openings, respectively, and resting at one 40 end portion adjacent its periphery against said annular shoulder, each of which die parts is formed with a die orifice defining the external form of one of said like shapes, separate like second die parts each removably received by and fitting one of said openings, respectively, and resting at one end portion adjacent its periphery against said first die part in that opening, each 45 of said second die parts being formed with a mandrel cooperating with the die orifice of the adjacent first die part, which mandrel defines the internal form of one of said like shapes, that face of each of said second die parts which is adjacent the associated first die part being formed to present a recess continuously and symmetrically surrounding said mandrel throughout the entire peripheral extent of said mandrel and communicating with the die orifice of said first die part throughout the entire peripheral extent of such orifice, the mandrel defining the inner lateral 55 side of said recess throughout the full circumferential extent of such side, each of said second die parts being formed with a plurality of uniformly distributed exterior longitudinally extending like grooves communicating with the adjacent recess for the full radial width of the latter and opening on the end face of said part opposite said recess.
